(57) **CLAIM**

The ornamental design for a storage drive, as shown and described.

DESCRIPTION

FIG. 1 is a top, front and side perspective view of a first embodiment of a storage drive embodying the new design. FIG. 2 is a bottom, back and side perspective view thereof. FIG. 3 is a top view thereof.

FIG. 4 is a bottom view thereof.

FIG. 5 is a first side view thereof.

FIG. 6 is a second side view thereof.

FIG. 7 is a front view thereof.

FIG. 8 is a back view thereof.

FIG. 9 is a top, front and side perspective view of a second embodiment with break lines.

FIG. 10 is a bottom, back and side perspective view thereof.

FIG. 11 is a top view thereof.

FIG. 12 is a bottom view thereof.

FIG. 13 is a first side view thereof.

FIG. 14 is a second side view thereof.

FIG. 15 is a front view thereof; and,

FIG. 16 is a back view thereof.

Broken lines are used to illustrate features of the storage drive which form no part of the claimed design. In the second embodiment, any portion of the storage drive between the break lines forms no part of the claimed design.
